UNITED STATES PATENT OFFICE.

JULIUS BRENZINGER, OF NEW YORK, N. Y., ASSIGNOR TO MAX AMS, OF SAME PLACE.

CAN-HEADING MACHINE.

SPECIFICATION forming part of Letters Patent No. 637,761, dated November 28, 1899.

Application filed August 28, 1899. Serial No. 728,687. (No model.)

To all whom it may concern:

Be it known that I, JULIUS BRENZINGER, a citizen of Germany, and a resident of New York city, county and State of New York, have invented certain new and useful Improvements in Can-Heading Machines, of which the following is a specification.

This invention relates to an improved machine for securing can-heads to flanged can-bodies by a double lap-joint.

The machine produces a large output, forms a perfect air-tight joint, is readily adjustable, and does not require skilled attendance.

In the accompanying drawings, Figure 1 is a front elevation of the machine; Fig. 2, a side elevation thereof; Fig. 3, a vertical section on line 3 3, Fig. 2; Fig. 4, a horizontal section on line 4 4, Fig. 1; Fig. 5, an enlarged section on line 5 5, Fig. 2; Fig. 6, a detail of part of roller 1; Fig. 7, an enlarged section on line 7 7, Fig. 2; and Fig. 8, a detail of part of roller m.

The letter a represents the frame of the machine, and b is the rotatable platform on which the can-body to be headed is supported. Above this platform is arranged a chuck c, adapted to bear upon the can-head and to rapidly rotate body and head simultaneously while they are subjected to the action of the 30 seaming-rollers.

Rotary motion is imparted to shaft c' of chuck c from pulley d' of power-shaft d by belt e, running over idlers e' and over pulley c' of shaft c'. The power-shaft d also drives 35 by belt f, running over idler f', a pulley g' loose on shaft g. This shaft is provided with a worm g', that engages a worm-wheel h', fast on shaft h, and is adapted to intermittently drive said shaft in manner hereinafter specified. The shaft h carries two cams i, j, that are adapted to project the seaming-rollers toward the work in the following manner: The first cam i, Fig. 5, is engaged by a roller i' of a lever i'', to the forward end of which is pivoted an upwardly-projecting wedge i''. This wedge when rising bears against the roller k' of a slide k, in the forked forward end of which the first seaming-roller l is pivoted. Thus the roller l engages the flanges A' B' of

the can-body A and cover B, and its profile 50 is so formed that it will bend them into a double lap-seam, Fig. 6. When the cam i allows lever i'' and wedge i'' to drop, the slide k will be drawn back by spring k''. In order to permit a delicate adjustment of the roller 55 l with relation to the work, I form back of wedge i'' an adjustable abutment, consisting of a pivoted bar i'', carrying antifriction-roller i''' and adapted to be fixed at different inclinations by set-screws i''. The cam j, Fig. 7, 60 actuates the second seaming-roller m in a similar manner by roller j', lever j'', wedge j'', roller n', and slide n, in the forward end of which the roller m is pivoted. The profile of this roller is such that it will flatten or 65 compress the seam doubled by roller l, Fig. 8, so as to form a flat air-tight joint. The abutment of wedge j'' is formed by the pivoted bar j'', carrying roller j''' and bearing against an elastic cushion or spring j'', the bar j'' being adjustable by bolt and nut j''. This elastic abutment permits the roller m to hug the contour of the can-body at the side seam and closely compress the lap-joint over such seam, so that imperfections in the joint and jamming are avoided. 70

The cam i is keyed to the shaft h, while the cam j is adjustably attached to cam i by means of set-screws j'', engaging elongated slots i'' of cam i. Thus the relative position 80 of the cams can be readily adjusted to adjust the movement of the seaming-rollers in their relation to one another.

In order to permit the slides to be set to can-bodies of different diameters, the shaft h 85 as well as the abutments and slides are supported by a carriage a', movable upon bracket a'' of frame a and held in position by set-screw a'', Fig. 3. The support b of can A is provided with a spindle b', stepped into the 90 upper end of a sliding bar o, embraced by sleeve a'' of frame a. The bar o is surrounded by a sliding collar o', Fig. 5, that constitutes the support for a pair of springs o'', over which is arranged a collar o'', adapted to be adjustably clamped to bar o by set-screw o''. After the can has been placed upon platform b the latter is raised, so that the can-head is 95

pressed tightly against chuck c . The raising of the platform is effected by means of a forked lever p , pivoted to sleeve a^4 at p' and engaging with its eccentric end p^4 a pair of 5 rollers o^4 of collar o' . The lever p may, if desired, be connected by chain p^3 to a treadle p^2 . When the lever p is swung down, the eccentric p^4 , by bearing against rollers o^4 , will lift rod o through collar o' , springs o^2 , and collar o^3 , and will thus press the can-head against the chuck c . The springs o^2 will form a yielding bed to compensate for slight differences in the height of the can-bodies. The connection between the can-support and 15 the worm-shaft g is such that when the can-support is raised the shaft will be once rotated to rotate cam-shaft h and project the seaming-rollers l m successively against the work. After the cam-shaft has made a complete rotation and the slides have been drawn back by the springs k^2 n^2 the worm-shaft is 20 arrested to arrest the seaming-rollers in their rearmost position, and the can-support is lowered ready to receive a fresh can-body. The construction for effecting these 25 results is as follows: The lever p is provided with an arm p^5 , connected by rod q to lever q' , carrying roller q^2 , that is engaged by a third cam r , fast on shaft h . To lever q' is secured one end of a spring s , containing a 30 core-rod s' and secured at its other end to a lever t , actuating clutch t' , by means of which the loose pulley g' can be coupled to its shaft g . When the lever p is depressed to raise the 35 can-support, the lever q' will be so vibrated that the draw on spring s will shift lever t to couple pulley g' to shaft g , and thus advance the rollers l m successively against the work. Meanwhile the roller q^2 will engage cam r , 40 and when the shaft h has made a complete turn the roller will be forced into the receding section of the cam-surface by a spring t^6 , secured to lever p . This will cause lever q' to be so vibrated that the core-rod s' will push 45 against the clutch-lever t to shift clutch t' , release pulley g' from shaft g , and arrest shafts g h .

The operation is as follows: The flanged can-body A , with the head B superposed, is 50 placed upon the platform b , and the latter is raised so that the head is pressed firmly against clutch c , by means of which head, body, and platform are rapidly rotated. The raising of platform b has coupled the shaft g to the power, and thus the cams i j are rotated 55 to raise the wedges i^8 j^8 and advance the rollers l m successively against the work, so as to first fold and then compress the seam. After the shaft h has made a complete turn, 60 the engagement of concave part of cam r with roller q^2 will cause the clutch t' to be shifted so as to uncouple pulley g' and arrest shafts g h . At the same time the lever p will be so vibrated as to lower its end p^4 and permit the 65 platform-support to drop and disengage the

can-head from the clutch c . The can which is now finished is removed and replaced by a new one, when the operation is repeated. The machine works with great accuracy and smoothness, is easily tended, and produces a 70 very large output.

What I claim is—

1. In a can-heading machine, a seaming-roller, a slide carrying the same, a cam, and a wedge adapted to be actuated by the cam 75 and engage the slide, substantially as specified.
2. In a can-heading machine, a seaming-roller, a slide carrying the same, a lever, a cam engaging the same, and a wedge pivoted 80 to the lever and adapted to engage the slide, substantially as specified.
3. In a can-heading machine, a seaming-roller, a slide carrying the same, means for actuating said slide, and a yielding buffer, 85 engaging the slide-actuating means, substantially as specified.
4. In a can-heading machine, a seaming-roller, a slide carrying the same, a wedge adapted to engage the slide, a cam for actuating the wedge, and a yielding buffer engaging 90 the wedge, substantially as specified.
5. In a can-heading machine, a pair of seaming-rollers, a pair of slides carrying the same, a pair of cams, a pair of levers successively operated by the cams, and wedges pivoted to the levers and adapted to engage the slides, 95 substantially as specified.
6. In a can-heading machine a roller adapted to fold the seam, a roller adapted to compress the seam, a pair of cams, and wedges actuated by said cams and adapted to successively advance said rollers, substantially as specified.
7. In a can-heading machine, a rotatable platform, a movable bearing for supporting said platform, a pair of seaming-rollers, and means for advancing the rollers against the work by the raising of the bearing, substantially 100 as specified.
8. In a can-heading machine, a rotatable platform, a movable bearing for supporting the same, a pair of seaming-rollers, means for advancing the rollers against the work by the raising of the bearing, and means for 105 automatically lowering the bearing, substantially as specified.
9. In a can-heading machine, a rotatable platform, a movable bearing for supporting the same, a worm-shaft, a loose pulley mounted thereon, a clutch operated by the bearing and adapted to couple the pulley to its shaft, a cam-shaft intergeared with the worm-shaft, 110 slides actuated by the cam-shaft, and seaming-rollers carried by the slides, substantially 115 as specified.
10. In a can-heading machine, the combination of the following elements: a driving-shaft, a worm-shaft, a cam-shaft intergeared therewith, a pair of cams mounted on the cam- 120
11. In a can-heading machine, a rotatable platform, a movable bearing for supporting the same, a worm-shaft, a loose pulley mounted thereon, a clutch operated by the bearing and adapted to couple the pulley to its shaft, a cam-shaft intergeared with the worm-shaft, 125 slides actuated by the cam-shaft, and seaming-rollers carried by the slides, substantially as specified.
12. In a can-heading machine, the combination of the following elements: a driving-shaft, a worm-shaft, a cam-shaft intergeared therewith, a pair of cams mounted on the cam- 130

shaft, slides actuated by the cams, seaming-
rollers carried by the slides, a rotatable plat-
form, an adjustable platform-support, means
actuated by the platform-support for coup-
pling the driving-shaft to the worm-shaft, and
means for automatically lowering the plat-
form-support, substantially as specified.

Signed by me at New York city, New York,
this 21st day of August, 1899.

JULIUS BRENZINGER.
